P. S. PITTINGER

HYPODERMIC NEEDLE

Filed Dec. 1, 1921

Inventor.
Paul S. Pittenger
by his Attorneys
Houson & Houson

UNITED STATES PATENT OFFICE.

PAUL S. PITTENGER, OF PHILADELPHIA, PENNSYLVANIA, ASSIGNOR TO H. K. MULFORD COMPANY, OF PHILADELPHIA, PENNSYLVANIA, A CORPORATION OF PENNSYLVANIA.

HYPODERMIC NEEDLE.

Application filed December 1, 1921. Serial No. 519,175.

To all whom it may concern:

Be it known that I, PAUL S. PITTENGER, a citizen of the United States, residing in Philadelphia, Pennsylvania, have invented
6 the Hypodermic Needle, of which the following is a specification.

One object of this invention is to provide a novel form of needle-containing package primarily designed to maintain an isolated 10 hypodermic needle in a sterile condition and permit of its convenient manipulation preparatory to its use without likelihood of its contamination or infection.

A further object of the invention is to 15 provide a hypodermic needle package having the above characteristics including means for holding a needle so that its points cannot engage any part of the package so as to be dulled or blunted thereby and which 20 in addition shall include means for removing a stylet from the needle without contaminating the latter.

The invention also includes novel means 25 for holding and directing the needle during the operation of inserting or positioning it in a hypodermic syringe, without contaminating it.

Another object of my invention is to provide a device of the above class with novel 30 means for indicating the order in which certain operations are to be performed in adapting it for use.

These objects and other advantageous 35 ends I attain as hereinafter set forth, reference being had to the accompanying drawings, in which,

The figure is an elevation of a hypodermic needle illustrating my invention as applied thereto.

40 In the above drawings 1 represents a hypodermic needle such as is commonly employed for the hypodermic injection of such substances as serums, vaccines, or the like and this consists of a relatively long, metallic tubular structure pointed at both ends and having permanently fixed to it, usually at a point nearer one end than the other, a flange or collar 2, formed of a metallic disc having its edge knurled or indented to permit of its being firmly grasped and immovably held by the fingers. For the purpose of insuring that the passage through the needle shall remain open until it is desired for use, there is usually mount-

ed in said passage an elongated wire or 55 stylet 3, one of whose ends projects beyond the end of the needle and is bent back upon itself as indicated in the drawing.

For maintaining both ends of the needle sterile until required for use I provide two 60 enclosing tubes 4 and 5 preferably of glass, each closed at one end and respectively provided with rubber or other suitable closures or stoppers 6 and 7. Each of these stoppers has a passage for the needle 1 and the tube 65 4 is of such a length as to completely enclose what in the present instance is the longer end 1^a of the needle, when the stopper 6 therein is in engagement with the disc or collar 2. Similarly the tube 5 is of such 70 length as to completely enclose the second and shorter end 1^b of the needle when the stopper 7 in its end is likewise in engagement with the disc or collar 2; it being noted that in both cases the pointed end of 75 the needle is held out of possibility of engagement with the glass tubes so that it cannot be injured thereby.

It is to be understood that before the assembly of the parts of my invention, each 80 of the stoppers or closures 6 and 7 has a preformed central passage which extends partly through it so that not only is the needle properly directed when it is inserted through each stopper, but it is caused to 85 pass axially, as is necessary to cause the two stoppers to be in alignment.

Under conditions of manufacture the stoppers 6 and 7 are applied to the opposite ends 90 1^a and 1^b respectively of the needle, the stylet 3 is introduced into the latter and the enclosing tubes 4 and 5 are applied to the stoppers. The whole combination is then subjected to a suitable sterilizing treatment, for which purpose it may be heated to and 95 maintained at such a temperature as to destroy all micro-organisms contained in or associated with any of the above described parts. After such treatment it is obvious that the two end portions 1^a and 1^b of the 100 needle will be maintained in a sterile condition and when it is desired to apply said needle to a hypodermic syringe it may be manipulated without the necessity of touching either of its ends.

105 For this purpose the collar or disc 2 is grasped by the fingers of one hand and the tube 5 with its stopper 7 is drawn off of the

end 1^b. Owing to the bend in the stylet 3, this is engaged by the stopper 7 and is withdrawn thereby from the passage of the needle. This exposed end 1^b may now be inserted through the rubber plug or other closure or seal of the barrel of a hypodermic syringe of suitable construction, after which, and while the collar 2 is still grasped by the fingers of the operator, the protecting tube 10 4 with the stopper 6 may be withdrawn from the end 1^a of the needle. The latter is now ready for use and it will be understood that the above operations may be performed without the necessity for touching either end 15 of the needle and thus contaminating the same.

In order to indicate the above described order of procedure, I preferably give one of the enclosing tubes 4 or 5, usually the latter, 20 some distinctive color so that an operator may be directed to remove this colored tubular cover from the needle as a first step in the use or application of the needle.

By means of the above described arrangement of parts it is thus possible to insure the hypodermic needle being maintained in a sterile condition until it is desired for use and to make possible its application to the syringe without the necessity for any part 30 of either of its ends being touched by the fingers or other object which might contaminate the same.

I claim:

1. The combination of a hypodermic needle; means including at least one closed tube enclosing one end of said needle; and a stylet mounted in the needle and formed to

be removed therefrom by the removal of said enclosing tube.

2. The combination of a hypodermic needle having a collar thereon; stoppers mounted on the needle on opposite sides of the collar; tubes enclosing the ends of the needle respectively and normally sealed by said stoppers; with a stylet in the needle 45 formed to be engaged and removed therefrom by one of the stoppers when this is removed from the needle.

3. The combination with a hypodermic needle of a pair of tubes having apertured stoppers through which the ends of the needle may be inserted, said stoppers being removable from the ends of the needles with the tubes and being adapted to fit closely around the needle to seal the tubes when the needle is inserted.

4. The combination with a hypodermic needle of a pair of tubes having apertured stoppers through which the ends of the needle may be inserted, the stopper of at least one of said tubes being detachable therefrom and removable from the needle with the tube, and each of said stoppers being adapted to fit closely around the needle to seal the tubes when the needle is inserted.

5. In combination, a hypodermic needle having a collar mounted thereon intermediate the ends thereof; stoppers removably mounted on the needle on opposite sides of said collar and abutting the same; and tubes enclosing the ends of the needle respectively, and normally sealed by said stoppers.

PAUL S. PITTINGER.
